UNITED STATES PATENT OFFICE

1,920,732

SPINNING CENTRIFUGE

Waldemar Zur Löwen, Wuppertal-Barmen, Germany, assignor to American Bemberg Corporation, New York, N. Y., a Corporation of Delaware

Original application August 11, 1931, Serial No. 556,428, and in Germany August 25, 1930. Divided and this application December 16, 1932. Serial No. 647,593

6 Claims. (Cl. 118—49)

- This invention relates to the manufacture of artificial silk and the like, and more particularly to the manufacture of artificial thread by the pot spinning process.
- 5 In the manufacture of artificial thread and the like by the above process, the thread is led from the precipitating bath to a suitable spinning pot. Heretofore the spinning pot has been so journaled as to be rotated and at the same time raised and lowered so that the thread, coming from the fixed guide tube may be laid evenly on the inner wall of the spinning pot. Such mechanism has been found to be cumbersome and inefficient due to the complicated mechanism 10 necessary to impart the desired rotary and reciprocating motion to the spinning pot.
- This mode of operation has been abandoned and the thread guide tubes have been reciprocated instead of the spinning pot which has been 15 journaled so as only rotary motion is imparted thereto. These thread guide tubes are secured to bars which are reciprocated by a cam drive through a common rocking shaft. As the motion is imparted from a main drive to a number of 20 filament guiding tubes the transmission gearing is necessarily complicated.
- The invention hereinafter described constitutes a divisional application of Waldemar Zur Loewen, filed August 11, 1931; Serial Number 25 556,428. In that application mechanism is described whereby each filament guiding tube has an independent drive thus reducing the number of operative parts and rendering the operation 30 of the machine more efficient.
- 35 It is an object of this invention to provide suitable housing for the spinning pot whereby motors of different sizes may be used without necessitating a change in the driving mechanism for the thread guide tube.
- 40 Another object of this invention is to provide a suitable housing for the spinning pot mechanism whereby the spinning systems now in use may be readily changed over to individual drives.
- 45 These and other objects of this invention will become more apparent from a study of the following description and the attached drawing in which the figure is a view of a spinning centrifuge mechanism enclosed in a suitable housing.
- The spinning pot 10, which is enclosed in a 50 housing 11, is driven through any suitable detachable connection by an electric motor 12. The motor is suspended in the housing by means of supports or brackets 13, and is separated from the spinning pot or centrifuge by the partition 55 14. The brackets are provided with recesses 15
- in which are located rubber cushions or gaskets 16 and upon which the upper rim 17 of the motor rests. To accommodate various sizes of motors a plurality of different sized supports or brackets 13 are provided.
- 60 Located on the bottom of the housing 11 is the housing 18 for the thread guide tube reciprocating mechanism. A shaft 19 is suitably journaled in the housing and projects therethrough directly below the motor. A flexible connection 65 20 is provided between the shaft and motor. A gear 21 secured to the shaft is adapted to drive the reduction gearing 22, cam drum 23, and thread guide rod 24, thereby imparting a reciprocating motion to the thread guide tube 70 25. The thread guide rod reciprocates in the bearing provided by the conduit 30. As may be clearly seen the driving mechanism encased in the housing 18 is completely immersed in the oil contained therein.
- 75 The electrical energy necessary to drive the motor is supplied through the plug 26 located in the bottom of the housing. The current is taken off through a cable 27 by means of a switch 28 actuated by the lever 29.
- 80 In operation the motor is started, rotating the spinning pot or centrifuge against the inner walls of which the thread is being placed. The thread guide tube is reciprocated, to insure the formation of a substantially even layer of 85 thread, by the motor through the flexible connection reduction gearing, cam drum and thread guide rod.
- 85 From the above description it will be appreciated that there has been provided a simple 90 and efficient means for providing each spinning pot or centrifuge and thread guide means with an individual drive thereby reducing the cost of operation and maintenance.
- 95 Although this invention has been described with reference to a specific embodiment thereof, it will be readily appreciated that the device is susceptible of many variations in the construction thereof without departing from the scope of the invention or of the appended 100 claims.
- 105 What is claimed as new is:
1. In a device of the class described, a spinning pot, a motor for rotating the same, a thread guide tube for laying thread in said spinning pot, a housing for said spinning pot and motor, resilient cushioning means associated therewith, and on which said motor is suspended and means for imparting reciprocatory motion to said thread guide tube comprising a shaft, a flexible connection 110

tion between said shaft and said motor, and means associated with said shaft to impart reciprocatory movement to said thread guide tube.

2. In a device of the class described, a spinning pot, a motor for rotating said spinning pot, a thread guide tube for laying thread in said spinning pot, a housing in which said spinning pot and motor are enclosed, resilient means for supporting said motor, means for reciprocating said thread guide tube including reduction gearing and a flexible connection between said reduction gearing and motor.

3. In a device of the class described, a spinning pot, a motor for rotating said spinning pot, a thread guide tube for laying thread in said spinning pot, a housing for said spinning pot and motor, supports secured to said housing, resilient cushioning means associated therewith and on which said motor is suspended, means for reciprocating said thread guide tube including reduction gearing, an oil tight housing therefor, and a flexible connection between said reduction gearing and said motor.

4. In a device of the class described, a spinning pot, a motor for rotating said spinning pot, a thread guide tube for laying thread in said spinning pot, a housing for said spinning pot and motor, supports secured to said housing, resilient cushioning means associated therewith

30

and by which said motor is suspended, means for reciprocating said thread guide tube, including reduction gearing, an oil tight housing therefore, and a flexible connection between said reduction gearing and said motor; a starter switch for said motor located within said spinning pot and motor housing.

5. In a device of the class described, a spinning pot, a motor for rotating said spinning pot, a thread guide tube for laying thread in said spinning pot a housing for said spinning pot and motor, supports secured to said housing, resilient cushioning means associated therewith and on which said motor is suspended, means for reciprocating said thread guide tube including reduction gearing, an oil tight housing therefor formed integral with said spinning pot and motor housing.

6. In a device of the class described, a spinning pot, a motor for rotating said spinning pot, a housing in which said spinning pot and motor is located, a thread guide tube, means for imparting reciprocatory movement thereto comprising a thread guide to which said tube is connected, a cam for reciprocating said thread guide, reduction gearing for rotating said cam and a flexible connection between said reduction gearing and motor.
